UNITED STATES PATENT OFFICE

147,151

DESIGN FOR A BATTERY CHARGER

William G. Schinske, Sycamore, Ill., assignor, by
mesne assignments, to Ideal Industries, Inc.,
Sycamore, Ill., a corporation of Delaware

Application July 30, 1945, Serial No. 121,058

Term of patent 3½ years

(Cl. D26—1)

To all whom it may concern:

Be it known that I, William G. Schinske, a citizen of the United States, residing at Sycamore, in the county of De Kalb and State of Illinois, have invented a new, original, and ornamental Design for a Battery Charger, of which the following is a specification, reference being had to the accompanying drawing, forming part thereof.

Figure 1 is a side elevational view of a battery charger, showing my new design;

Figure 2 is a front elevational view; and

Figure 3 is a top plan view thereof.

I claim:

The ornamental design for a battery charger, as shown.

WILLIAM G. SCHINSKE.
